SIGNORS TO THE INTERSTATE FOLDING BOX COMPANY, OF MIDDLETOWN, OHIO.

MEANS AND METHOD FOR MAKING PAPER BOXES AND THE LIKE.

Application filed November 11, 1925. Serial No. 68,458.

This invention relates to improved means and a new method or process for making paper boxes, or the like.

The use of paper boxes in a great variety 5 of forms having attained enormous proportions in a market which is becoming more and more exacting in its requirements, better boxes at lower prices are demanded. Thus improvements in the means and methods 10 of production which tend to cheapen and at the same time to maintain or improve the quality of the product are of the greatest importance.

The present invention is a radical departure 15 from the prevailing practice of paper box making, the new means and method herein set forth being fundamental in the art and the objects attained by the invention—higher quality of product at low 20 cost of production—are a long step forward of the heretofore common practice.

The departure from the common practice 25 comprised in the invention is based on the use of a new element—double faced adhesive tape—for forming the box joints, new means—an automatic apparatus—for applying the adhesive element to the paper sheets before the box blanks are cut therefrom, and new designs of boxes made possible by and 30 adapted to the new practice.

It will be obvious from the nature of the 35 invention that its general practice will give rise to various forms of machinery—hand machinery, semi and fully automatic machinery for practicing the invention, and to a diversity of forms of boxes adapted to be produced by the new method.

We desire it to be understood, therefore, 40 that the invention as herein set forth is for the purpose of illustrating the new principle of means and methods for making paper boxes and further to illustrate suitable forms of the product without specific limitations as to these illustrations, the underlying principles and the fundamental spirit 45 of the invention being the premise upon which the presentation of the invention in the accompanying drawings, the detailed specification and the appended claims is 50 made.

In the general practice of the invention it is contemplated that the box blanks will be cut from the paper sheets prepared with adhesive on blank cutting and scoring machines commonly used in the industry, that 55 the blanks will be carried as stock by the manufacturer, or furnished as stock to the customer, to be made up into assembled boxes as required for use, the blanks requiring only the application of moisture thereto 60 to render the tape adhesive for assembling the boxes.

In the drawings:

Fig. 1 is a side elevation of the tape applying machine;

Fig. 2 is a plan view of the machine;

Fig. 3 is a view in elevation at the receiving end of the machine;

Fig. 4 is a longitudinal sectional view of the machine on line 4—4 of Fig. 3;

Fig. 5 is a sectional view taken on line 5—5 of Fig. 1;

Fig. 6 is a sectional view taken on line 6—6 of Fig. 1;

Fig. 7 is a sectional view taken on line 7—7 of Fig. 1;

Fig. 8 is a sectional view taken on line 8—8 of Fig. 1;

Fig. 9 is a detail sectional view taken on line 9—9 of Fig. 8;

Fig. 10 is a sectional view taken on line 10—10 of Fig. 8;

Fig. 11 is a detail view of the tape feeding mechanism;

Fig. 12 is a sectional view on line 12—12 of Fig. 3.

Figs. 13, 15, 16 and 17 illustrate various types of paper boxes adapted to be made by the improved method of construction;

Fig. 14 illustrates a modified type of machine for applying the adhesive tape to the paper.

Fig. 18 is a view in perspective serving to illustrate conventionally a common type of box blank cutting and scoring machine.

The tape applying apparatus as illustrated in Figs. 1 to 12 is supported in a suitable frame 1, the front end of the machine being provided with a feeding table 2 for supporting the paper sheets as the same are 100

fed manually, as here shown, to the machine, a receiving table 3 for the sheets being provided at the rear of the machine.

As best shown in Figs. 3 and 4 the adhesive tape is supported in rolls 4 rotatable on shafts 5 having their ends free in slots 6 of brackets 7. The tape 8 is drawn from the rolls 4 over guide rollers 9 and tape moisteners which, as here shown, consist of an endless web 10 operable over rollers 11, 12, 13 and 14 and through a liquid container 15. Rollers 11 are mounted on a shaft 16 and are each provided with teeth 17 which act to engage the webs 10 to prevent slipping of the webs on the rollers. Shaft 16 is driven by a chain 18 and sprockets 19-20, sprocket 20 being mounted on a shaft 21 supported transversely in the lower frame structure 1. Operating movement is being imparted to shaft 21 by means of a pawl and ratchet drive 22-23, illustrated in detail in Fig. 11, the pawl being pivoted on the end of a spring tensioned plunger 24 operable in a housing 25 and actuated in one direction by a cam 26 and in the opposite direction by a spring 27. Both the tape supply roll supports 7 and the tape moisteners are adjustable laterally of the machine by means of clamps 28-29 which serve to secure these parts to transverse frame members 1^a-1^b, adjustment of the tape and the coacting parts serving to adapt the machine for applying the tape in any desired relation to the paper sheets.

As best shown in Fig. 4, the paper sheets 30 are fed to the machine from table 2 by a first set of feed rollers 31-32 supported on shafts 33-34, the sheets being presented to the rollers manually. Shaft 33 is supported at its opposite ends in arms 35 pivoted at their forward ends as at 36 and spring tensioned at their opposite ends by springs 37 (see Fig. 1), the upper ends of the springs being connected to threaded bolts 38 extended through the inner ends of the arms and provided with adjusting nuts 39 for adjusting the tension of the springs, thus to regulate the feeding pressure between rollers 31-32. To present the sheets of paper properly to the feed rollers and to align and guide the sheets as the same are fed between the rollers, a series of longitudinally extended guides 40 are provided, the guides being supported on brackets 41 depending from a shaft 42 and spaced one from another transversely of the machine as best shown in Figs. 2 and 3.

The sheets of paper are advanced by feed rollers 31-32 to the second set of feed rollers 43-44 supported on shafts 45-46, as best shown in Fig. 8, the ends of the shaft 45 being supported in opposite arms 47 pivoted as at 48 and spring tensioned, as best shown in Fig. 1, by parts 49, 50 and 51, in a manner similar to roller 31 to regulate the

pressure between rollers 43-44. Opposite supplemental feed rollers 52 are also supported on shaft 45 and set on the outer margins of the paper sheets.

The paper sheets are fed to the machine by an attendant, or by suitable sheet feeding mechanism of well known construction, in a manner to cause the rear edge of the leading sheet to be overlapped by the front edge of the following sheet as indicated in Fig. 9.

The sheet spacing mechanism is supported on shaft 45 and includes tripping mechanism for governing the intermittent rotation of the shaft, the mechanism consisting as best shown in Fig. 10 of a collar comprising large and small portions 57-58, portion 58 having a recess 59 in which a spring 60 is located. Coacting with recess 59 and spring 60 is a trip member comprising an upwardly extended arm 61, having a pin 63 secured in its free end, and a downwardly extended arm 66 having a roller 62 supported in its free end, the roller being raised above the plane of the sheets of paper in one position and lowered below the plane of the sheets in its other position. The trip member is pivoted on a stud 65 supported in a collar 66 secured to a shaft 67 (see Fig. 2). The collar 57 has a pin 64 adapted to engage pin 63 in a camming action to effect the downward movement of roller 62 which rests lightly on the sheet as the rear edge of the sheet passes under it, the end of the arm 66 acting in the lowered position to stop the following sheet of paper as shown in Fig. 9. The movement of the stop mechanism is very rapid and is timed to effect spacing of the sheets one from another at a distance approximating the diameter of roller 62. Clearance for roller 62 in its downward movement is provided in the bed plate of the machine as indicated at 55 in Fig. 9.

From feed rollers 43-44 the sheets pass successively between feed rollers 68-69, tape perforating or severing rollers 70-71, feed rollers 72-73 and feed rollers 74-75, to the receiving table 3, the relative relation of the rollers one with another being best shown in Fig. 4.

The adhesive tape is applied to the sheets between feed rollers 68-69, the tape being drawn from the supply roll 4 over guide rollers 9, coming in contact with the moistening device as it descends to the sheets, firm adhesion of the tape to the sheets being effected by the pressure of the feed rollers.

Means are provided in connection with the tape guides 9^c to prevent sticking of the tape, which has then been moistened, to the rollers, the mechanism consisting of opposite spacing fingers 10^c (see Fig. 4) which act to align the tape and direct the same to guides 9^c, and a fin of metal 11^c secured in the shaft 12^c upon which guide rollers 9^c

are supported, a lever 13^a being secured to the shaft for turning the same to cause strip 11^c to move against and raise the tape off the guide rollers. Associated with each feed 5 roller 68 is a scraper 9^b supported in a laterally adjustable bracket 10^b on a cross shaft 11^b upon which the tape guide rollers 9^c are supported.

Provision is made in the machine, as illustrated in Fig. 1, for applying the tape to both sides of the sheets, this being a time saving feature in taping the sheets for boxes requiring the adhesive on both sides of the box blanks. The added means for 10 taping consist of a second set of mechanisms substantially the same as that described and identified by reference numerals 4 to 29 inclusive, except that the direction of movement of the tape is upward to the under 15 side of the sheets of paper. The main features of the lower taping mechanism which have their counter-parts in the upper mechanism are indicated respectively as 4^a to 15^a inclusive, the actuating mechanism illustrated in Fig. 11 being common to both sets 20 of taping mechanism.

The driving mechanism for the machine and various controls for the feeding mechanism are best illustrated in Figs. 1, 2 and 30 3, details of the mechanism being further illustrated in Figs. 5, 6, 7 and 8.

The main drive connection of the machine is shaft 76 which may have any suitable connection to the source of power. The connection from the drive shaft to lower feed roller 32, as best shown in Figs. 1 and 2, is 35 through gears 77, 78, 79, 80, 81, 82, sprocket gears 83, 84 and sprocket chain 85.

In order to provide a flexible connection 40 to feed roller 32, sprocket wheel 84 is mounted on a sleeve 86 operable free on shaft 34, the sleeve constituting one member of a friction clutch of which the opposite member 87 is keyed slidably on shaft 34, the adjacent end of the shaft being threaded and provided with a wheel nut 88, and a spring 89 interposed between the nut and part 87 to regulate the driving tension of the clutch, a fiber disc 90 being interposed between the 45 clutch members 86-87 to effect the desired frictional relation therebetween. The driving connection from lower feed roller 32 to upper roller 31 is inside the frame of the machine through gears 91-92 and a friction 50 clutch 96, the outer member of which is pinned to shaft 33. Gear 92 and the inner member of the clutch operate as an integral part free on shaft 33 and are held in the desired frictional relation of the clutch by 55 means of an adjusting nut 97 and a tension spring 98 on shaft 33.

The connection from the drive shaft 76 to lower feed roller 44 is through gears 77, 78, 79, 80, 81, 82, sprockets 83-99 and chain 85, 60 a slack adjuster 100 being applied to the

chain (see Fig. 1) to effect proper driving relation between the chain and sprocket 99. The driving relation of sprocket 99 to shaft 46 being frictional, similar to the frictional driving mechanism for shaft 34, and consisting of clutch members 101, 102, 103, the adjusting nut and spring 104, 105. Upper shaft 45 is driven positively from shaft 46 through gears 106, 107, gear 106 operating as an integral part with the outer clutch member 102 and a sleeve 108, the latter being provided with a trip pin having a function which will presently be described. 70

The auxiliary feed rollers 52 which are mounted free on shaft 45 are driven by 80 gears 110, 111, the latter gears being fixed on shaft 46, each gear 110 having an annular flange 112 coating with an annular groove 113 in the adjacent roller 52 to prevent axial displacement of the rollers. 85

The connection from drive shaft 76 to lower feed roller 69 is through gears 77, 78, 79, 80, 81 and 82 the last named gear being secured to shaft 114 as best shown in detail Fig. 7. Also secured to shaft 114 outside 90 the frame 1 is the sprocket gear 83, a second sprocket 122 and the inner member of a friction clutch 123, 124, 125. Supported free on shaft outside the clutch is a cam disc 126 and a tripping collar 127 operating as an 95 integral part. The collar has a trip pin 130 and is adjustable rotatably on a hub 128 of the cam disc and secured thereon by a set screw 129. The tension of the friction clutch is regulated by a nut wheel 131 and 100 spring 132 on the end of the shaft 114.

The connection from drive shaft 76 to the tape severing rollers 70 and 71 is through gears 77, 78, 79, 80, 81, 82, the sprocket gear 122, chain 133 and sprocket gear 134 free on shaft 116 upon which lower 105 rollers 71 are supported, the connection from roller 71 to roller 70 being through gears 135, 136, as best shown in Fig. 6. The driving connection from sprocket gear 134 to shaft 116 is a friction clutch comprised of an inner recessed clutch disc 137, an outer disc 138, intermediate discs 139, 140 and fiber discs 141, disc 137 and the inner fiber disc being interengaged one with the other as indicated at 142 (see Fig. 1) to effect a positive driving relation therebetween. Clutch disc 138 has an outwardly extended hub 143 which is splined on shaft 116 as indicated at 115 144 thus effecting a positive driving connection between the shaft and the outer clutch member. Operable as an integral part with clutch disc 138 is a sleeve 145 having at its inner end a lock collar 146 and outwardly of the collar a trip pin 147. The tension of the 120 clutch is regulated by a wheel nut 148 and spring 149 on the end of shaft 116.

To effect partial or complete severing of the tape, as may be desired, the lower rollers 71 are each provided with severing or perforating 125 130 135 140 145 150 155 160 165 170 175 180 185 190 195 blades 150, and the upper roller 70 with a clearance recess 151 for the blades, a severing action on the tape resulting as the blades and recess meshes one with the other upon each 5 complete turn of the rollers.

The connection from drive shaft 76 to feed rollers 73, 73, is through gears 77, 78, 79, 80, 82^a, and 152, the latter gear being secured to shaft 118 on which roller 73 is supported, the 10 upper roller 72 on shaft 119 being driven by frictional engagement with roller 73.

The connection from gear 152 to feed rollers 74, 75 is through gears 153, 154 and 155, the two latter gears being secured respectively to shafts 120, 121 upon which the rollers are mounted. Supported on shaft 120 outside the frame 1 is a friction clutch comprised of opposite discs 156, 157 and an intermediate fiber disc 158, disc 156 being fixed 20 on the shaft. Operable as an integral part with disc 157 free on the shaft is a cam disc 159 and a lock disc 160, the tension of the clutch being regulated by a wheel nut 161 and a spring 162 adjustable on the end of the 25 shaft.

The controls for effecting timing of the different units of the sheet feeding mechanism consist, as best shown in Figs. 1 and 2, of trip and stop mechanism interposed between the feeding rollers 43—44 and 68—69, consisting of a rocker arm 163 pivoted as at 30 164 and spring tensioned in clockwise direction by a spring 165, the upper end 166 of the arm coacting as a pawl with the cam disc 126 (see Fig. 7) on shaft 114, the lower end 35 of the arm having a flat cam face 167 adapted to be engaged by a trip pin 109, as lower roller 44 approaches completion of each cycle of rotation, which acts to rock arm 163 in counter-clockwise direction, thus releasing cam 126 and starting rollers 68—69 to rotate just before completion of rotation of 40 rollers 43—44 which acts to advance the leading sheet of paper relative to the following sheet sufficiently to take up the overlap of 45 the sheets illustrated in detail Fig. 9, limited spacing between the sheets being effected by the foot 62 of the trip mechanism illustrated in Fig. 10 as described.

The second unit of the feed roller controlling mechanism consists of a rocker arm 168, pivoted at 169 and spring tensioned in clockwise direction by a spring 170, the upper end 171 of the arm coacting as a pawl with the 55 cam disc (see Fig. 6) on shaft 116, the lower end of the arm having a cam face 172 adapted to be engaged by the trip pin 130, as lower roller 69 rotates, which acts to rock arm 168 in counter-clockwise direction, thus disengaging cam 146 and permitting rollers 60 70—71 to rotate, the severing devices 150 being located in the lower roller to intersect the adhesive tape between the sheets.

The controlling mechanism for the last 65 set of feed rollers 74—75 consists of a rocker

arm 173, pivoted at 174 and spring tensioned in clockwise direction by a spring 175, the upper end 176 of the arm coacting as a pawl with the cam disc 160 (see Fig. 5) on shaft 120, the lower end of the arm 70 having a cam face 177 adapted to be engaged by the trip pin 147, as lower roller 71 rotates which acts to rock arm 173 in counter-clockwise direction, thus disengaging cam 160 and permitting rollers 74—75 75 to rotate to deliver the sheets to the receiving table 3.

Rollers 74—75 are of larger diameter and exert a faster feed on the sheets than rollers 72—73, the provision being for the purpose of completely separating the sheets one from another in event of only partial severing of the tape being made by the devices 150—151. To this end rollers 74—75 have an intermittent feeding action on the paper, accomplished by raising and lowering of the upper roller by means of eccentric sleeves 178 secured to a shaft 179 supported in brackets 189 connected to a crank arm 180 in turn connected to a rocker arm 181 pivoted at 80 182 and having its lower free end 184 coacting with the cam 159 on shaft 120, the rocking of the arm acting to rotate the eccentric sleeves 178 and to raise and lower roller 74, thus to effect an interrupted feeding relation of rollers 74—75. To this end shaft 121 is supported in floating bearing 185 operable in guides 186, the bearings being spring tensioned by opposing springs 187—187^a, and shaft 179 by springs 179^a. The eccentric sleeves 178 are supported in open bearings 188 formed on the upper sides of bearing blocks 185. When the cam follower 184 of rocker arm 181 is in engagement with portion 190 of cam 159 upper roller 74 will be raised and the feeding action between rollers 74—75 will be interrupted, the end of the sheet during this interval being advanced between the rollers by the action of feed rollers 72—73. The feeding of the sheets upon lowering of roller 74 being faster than the feeding action of rollers 72—73, the adhesive tape will be completely severed, if only partially severed by the action of the devices 150, thus the sheets will be separated as delivered to 95 100 105 110 115 120 125 130 table 3.

From the foregoing detailed description and the drawings for illustrating the invention, the underlying principles of the invention and the objects attained will be understood by those skilled in the art to which the invention relates. It will be observed that the adhesive tape can be applied as desired to one or both sides of the paper sheets with any suitable spacing between the tape as may be required to suit the construction of the box. Obviously, by passing the sheets through the machine the second 130

time the tape can be applied in two directions on the sheet, one at right angles to the other, thus adapting the sheets as provided with the adhesive element for the entire 5 range of paper boxes, in all the variations of shapes and sizes, in which portions of the box are folded one part relative to another at right angles to form the joints of the boxes.

10 An important feature of the invention is in connection with the first set of feed rollers 31—32 which have the further function of aligning the paper sheets as the same are advanced between the rollers. To this 15 end the upper roller is driven through the friction clutch 96 and by the action of the paper on the rollers. As the forward end of the sheet is moved against the trip stop arms 62 the resistance to the sheet will act 20 to stop rollers 31 while lower rollers 32 continue to rotate, the action of the lower rollers on the paper being to move the forward end of the sheets into engagement with the 25 opposite sets of stops 62 and thus to align the sheets to the plane of movement through the machine.

It will be obvious that the paper for the box blanks may be supplied from a roll and the web severed into sheets of desired 30 lengths. A general form of a machine suitable for preparing the sheets by this method is illustrated in Fig. 14. The several groups of the mechanisms are supported, as here shown, in a main frame 200, the roll of paper 201 being supported in separate opposite frames 202. The web of paper 203 as drawn from the roll is given the desired tension by a set of friction rollers 204, 205, 206, adjustment of the latter roller relative 35 to the others being provided by means of the pivoted arm 207, in which the roller is supported, and the slotted bracket 208 and lock nut 209. Three sets of feed and pressure rollers—210—211, 212—213, 214—215, 40 act successively on the paper to feed it through the machine and to apply the adhesive tape in the manner described, the tape being supplied from rolls 216 and moistened by a device 217 similar to that described. A sheet and tape severing device 45 is interposed, as here shown between rollers 212—213 and 214—215, consisting of a blade 218 mounted on a reciprocating head 219 operable by an arm 220 connected to a rod 50 221 which in turn is connected to a rocker arm 222, the latter being actuated by a cam 223.

The driving connections of the machine 55 consist of the main drive shaft 224 which is provided with a power pulley 225 and is connected to rollers 210—211 by gears 226, 227, 228, 229 and 230, rollers 212 and 213 being operably connected one to the other by gears 227—231, and roller 215 connected to 60 roller 213 by sprockets 232—233 and chain

234, the upper roller 214 being driven from roller 215 by friction. The cam 223 is driven through gears 226 and 235. To vary the lengths of the sheets of paper it is contemplated to use change gears 226—235 of 70 different ratios.

This invention is further illustrated in Figs. 13, 15, 16 and 17 in which representative designs of boxes, of novel construction, adapted to be produced by the practice of 75 the invention, are illustrated. The products as here shown serve to further illustrate the fundamental improvements in the art of paper box making comprised in the invention.

Figs. 15, 16 and 17 illustrate a three piece box in which the tape *v*—*w*—*z* is applied to opposite sides of the sheet, the box being adapted to be sealed on all adjoining edges 80 as set up.

Fig. 13 illustrates the paper blanks, in three pieces, from which the box is made up, all the blanks being adapted to be cut from sheets to, which the adhesive element is applied on the machine herein described, the 85 method being to tape the sheets on the machine, cut the blanks as illustrated in Fig. 13 and set up the box, assembling of the boxes being done in the general practice by the user who is furnished the boxes knocked- 90 down and he sets them up as required for distributing his products.

As shown in Fig. 13 the adhesive tape *m*—*n* is applied to the sheets to cause the tape to come to edges of the blanks which form the joints, the strips of tape *n* being extended at right angles to the strips *m*.

It will be obvious from the several forms of boxes illustrated in the drawings adapted to be made by the improved means and method herein set forth that the principle of the invention is universal in its adaptation to the making of paper boxes in which adhesive joints are used in the construction and, furthermore, that the invention serves to enlarge the field of design of boxes of improved construction in forms heretofore unknown. Thus the invention has revolutionary force in the art of making paper boxes, more especially in the branch of the art where production in large volume is effected by automatic or semi-automatic machinery, the outstanding advantages in the saving of time, labor and material costs, and gain in the quality of the product being of great 105 importance.

The box blanks may be cut from the paper sheets by any suitable means, as the common type of blank cutting and scoring machine illustrated in Fig. 18. The machine as here shown consists of a feed table 300, a cylinder 301 for moving the sheets relative to a matrix or die 302 supported on a reciprocating table 303, the cutting and scoring of the blanks being effected as the matrix 110 115 120 125 130

is moved into engagement with the sheets on the cylinder.

The adhesive element as herein described and illustrated in the practice of the invention is double faced adhesive tape. It will be understood, however, that this is for the purpose of illustration only and that it is contemplated to use an adhesive of any form suitable to the practice of the invention.

10 Having described our invention, we claim:

1. In the art of paper box making the herein described method of production consisting in causing a sheet of paper to be moved in a given plane in causing a strip of 15 an adhesive element to move in a plane parallel to the plane of movement of the sheet, in causing adhesion between said element and sheet incident to the forward movement thereof, in cutting a box blank from said 20 sheet according to the position of the tape thereon and forming the box by effecting adhesive joints through the instrumentality of said element.

2. In the art of paper box making the 25 herein described method of production consisting in causing a sheet of paper to be moved in a given plane, in causing an adhesive element to contact with moisture and to be moved in a plane parallel to the plane of 30 movement of said sheet, in causing adhesion between said element and sheet incident to the forward movement thereof, in cutting a box blank from said sheet and forming a box by effecting adhesive joints through the 35 agency of said element.

3. A taping machine including in combination, a series of feed rollers acting to feed sheets of paper therebetween and means 40 coacting with one of the feed rollers for spacing the sheets one from another, means to support a roll of adhesive tape, means to direct the tape into engagement with said sheets as the sheets are engaged by said rollers, means for moistening one side of the 45 tape to effect adhesion between the tape and said sheets, and means acting to sever the tape between adjacent sheets.

4. A machine of the character described 50 including in combination, a series of feed rollers for advancing sheets of paper, timed one with another to cause overlapping of the front and rear edges respectively of adjacent leading and following sheets, and a member acting as a stop for the following 55 sheet and operable between the sheets to effect spacing of one sheet from another.

5. A machine of the character described 60 including in combination, a series of feed rollers for advancing sheets of paper, timed one with another to cause overlapping of the front and rear edges respectively of adjacent leading and following sheets, and a member operably associated with certain of 65 the feed rollers resting normally free on the advancing sheet and operable between the

sheets to stop the following sheet and to effect spacing of one sheet from another.

6. A taping machine including in combination, feed rollers coacting one with the other to advance sheets of paper therebetween, one sheet overlapping another, one of the rollers being friction driven, mechanism acting to stop the movement of each sheet and thereby stopping the friction driven feed roller, the coacting feed roller 75 acting to align the sheets one with another, means to reduce the overlap of the sheets and means acting to direct strips of adhesive tape to said sheets and to effect adhesion of the tape to the sheets following said alignment.

7. A taping machine including in combination, means for advancing a sheet of paper, means for advancing a strip of adhesive tape in a plane parallel to the plane of 85 movement of the paper, means to prevent adhesion of the tape to operable parts of the machine when said machine is at rest, and pressure means for effecting adhesion between the tape and the paper.

8. A taping machine including in combination, a series of sets of feed rollers for advancing sheets of paper, means for applying strips of adhesive tape to the sheets incident to the movement thereof, means 95 interposed between sets of the feed rollers for severing the tape between sheets and means for accelerating the movement of the sheets after said severing operation to effect increased spacing between the sheets.

9. A taping machine including in combination, a series of sets of feed rollers for advancing sheets of paper, means for applying strips of adhesive tape to the sheets incident to the movement thereof, means interposed between sets of the feed rollers for severing the tape between sheets and means comprising rollers having an intermittent feed and acting to accelerate the movement 105 of the sheets after said severing operation 110 to increase the space between sheets.

10. A taping machine including in combination, coacting sets of feed rollers for advancing sheets of paper successively, said rollers being timed one set relative to the other to cause the rear edge of the leading sheets to be overlapped by the front edge of the following sheet, stops in engagement with and rendered inoperative by the leading sheet and acting to interrupt the movement of and to align the following sheet, said stops upon the leading sheet moving out of engagement therewith acting further to release the following sheet and to space one sheet from the other.

11. In the art of paper box making the herein described method of production consisting in causing a sheet of paper to be moved in a given plane, in causing a strip of double faced adhesive tape to be mois-

tened on one side and to be moved in a plane parallel to the plane of movement of the paper, in causing adhesion between the tape and paper incident to the movement thereof, 5 in cutting box blanks from said sheet and in forming a box from said blanks by moistening the opposite side of the tape and effecting adhesive joints by means of the tape between coacting portions of said blanks.

In testimony whereof, we affix our signatures.

SAMUEL BERGSTEIN.
ARTHUR C. E. LINDNER.
